US0D1095015S

(12) **United States Design Patent** (10) **Patent No.:** **US D1,095,015 S**
(45) **Date of Patent:** **** Sep. 30, 2025**

(54) **KNIFE SHEATH**

(71) Applicant: **Alliance Sports Group, L.P.**, Roanoke, TX (US)

(72) Inventors: **David Justis**, Stillwater, OK (US); **Frederick Karl**, West Linn, OR (US)

(73) Assignee: **ALLIANCE SPORTS GROUP, L.P.**, Roanoke, TX (US)

(**) Term: **15 Years**

(21) Appl. No.: **29/920,493**

(22) Filed: **Dec. 11, 2023**

(51) **LOC (15) Cl.** **03-01**

(52) **U.S. Cl.**

USPC **D3/220**; D3/221; D3/228; D22/118

(58) **Field of Classification Search**

USPC D3/220, 221, 228; D22/118

CPC B26B 29/02; B26B 29/025; B26B 3/06

See application file for complete search history.

(57) **CLAIM**

The ornamental design for a knife sheath as shown and described.

DESCRIPTION

FIG. 1 is an elevated, perspective view of a knife sheath in accordance with my invention;

FIG. 2 is a side view of my invention as shown in FIG. 1; FIG. 3 is a side view of my invention as shown in FIG. 1, an opposing side view being the mirror image thereof; and FIG. 4 is a top view thereof;

FIG. 5 is a bottom view thereof;

FIG. 6 is an end view, taken from the left side of FIG. 1; and, FIG. 7 is an end view, taken from the right side of FIG. 1. The broken lines shown in FIGS. 1-7 the drawings are to show environment and form no part of the design.

1 Claim, 3 Drawing Sheets
